DISPENSING CARTON

Kenneth T. Butterly, Kalamazoo, Mich., assignor, by mesne assignments, to KVP Sutherland Paper Company, a corporation of Delaware.

Filed Dec. 23, 1957, Ser. No. 704,634

6 Claims. (Cl. 229—17)

This invention relates to a dispensing carton adapted for use in packaging various types of materials.

The main objects of this invention are:

First, to provide a dispensing carton, which may be and is preferably formed of an integral blank and is well adapted for packaging relatively heavy materials and at the same time may be quickly opened without the aid of implements and thereafter repeatedly opened and closed.

Second, to provide a carton having these advantages which is economical in the amount of stock required in proportion to its size and one which may be readily set up and filled and closed.

Objects relating to details and economies of the invention will appear from the description to follow. The invention is defined and pointed out in the claims.

A preferred embodiment of the invention is illustrated in the accompanying drawing, in which:

Fig. 1 is a perspective view of a closed carton embodying my invention.

Fig. 2 is a perspective view illustrating one step in the opening thereof.

Fig. 3 is a fragmentary perspective view illustrating the carton in fully opened position.

Fig. 4 is a fragmentary perspective view illustrating structural details of the carton.

Fig. 5 is a plan view of the carton blank.

Fig. 6 is a fragmentary plan view illustrating the manner in which the blank may be stamped or dyed from a sheet of stock.

In the accompanying drawing I have illustrated a carton embodying my invention as containing a plurality of packages 1 but it should be understood that while adapted for individual packages it is also adapted for loose contents, or contents enclosed in a single package as is common practice with various food products.

While I use the terms "side" and "end" walls, it will be understood that they are used for convenience in designating relative relation of the parts rather than in relation to shape.

The embodiment of my invention illustrated is formed of an integral blank comprising side walls 2 and 3 and end walls 4 and 5 connected by hinging or folding scores 6. The sealing flap 7 is connected to the side wall 3 by a folding or hinging score 6.

In the embodiment illustrated, the sealing flap 7 is dimensioned to correspond to the end walls with the exception that it has a notch 8 at its upper end which serves as a finger opening as will appear as the description proceeds. This sealing flap is arranged on the inner side of the end wall 4 and it serves as a reinforcing member therefor.

The side walls are provided with bottom closure members 9, the end wall 5 with the bottom closure member 10 and end wall 4 with the bottom member 11. These bottom closure members are disposed in overlapping relation and adhesively secured together as is common practice in cartons of this type and therefore the relation

2

of these parts in the erected bottom is not illustrated. The shape of the end wall bottom member 11 has nothing to do with its functioning but is the result of other structural features which will be pointed out as the description proceeds.

The top closure comprises the side top closure members 12 and 13 respectively and the end closure members 15 and 16. The side top closure member 12 is the inner top closure member and terminates at one end thereof in spaced relation to the end wall 4 as is illustrated in Figs. 4 and 5, that is, in other words its edge 17 is spaced from the corresponding edges of the side walls 2 and 3.

The outer side top closure member 13 is provided with a tongue or finger piece 18 which projects beyond the edge 17, its tip or edge 19 is desirably rounded as illustrated, and extends to the end wall 4, see Fig. 1. The top closure member 16 is substantially longer than the end top closure member 15 as is clearly illustrated in Fig. 5.

10 The side top closure members 12 and 13 are provided with transverse, desirably registering, fracturing or tear zones 20. The top closure members between these fracturing zones 20 and the corresponding ends of the side top closure members are severable or fracturally connected to their respective side walls by the weakening scores indicated at 21, see Fig. 5. These fracturing scores or zones 20 and 21 define removable top closure sections 22 which are adhesively bonded together so that they may be removed as one piece by the grasping of the finger piece 18 which, as stated, projects beyond the edge 17.

15 The end wall 4 is provided with a transverse hinging score 23 which renders the upper portion of the end wall 4 swingable and the end top closure 16 is hingedly connected at 25 to the upper edge of this swingable section 24. The end top closure member 16 is of such length that when in closed position its end projects beyond the edge produced by the removal of the top closure portion 22, as is indicated by dotted lines in Fig. 2. With the section 22 removed the top closure member 16 constitutes a closure for the resulting opening and the carton may be opened and reclosed by manipulation of the swinging section 24. A tab 26 projecting from the edge of the closure member 16 overlies the adjacent side wall 4 and serves as a guide in inserting the closure member 16 below the overlapping side closure members, as is illustrated in Fig. 2.

20 The swingable section 24 of the end wall 4 has a fracturable connection 27 to the side wall 2. This prevents the swingable section 24 from swinging outwardly until after this connection is broken.

25 It will be noted that the blank shown in Fig. 5 is of substantially rectangular angular outline. However the end closure flap 16 projects beyond the edges of the other top closure flaps. In Fig. 6 I have illustrated how these blanks may be stamped from sheet stock and the extended portion of the closure member 16 resulting in the shortening of the bottom closure member 11, as indicated at 28.

30 As stated, the carton is designed to facilitate opening without the use of implements. To open it is only necessary to grasp the finger piece and pull upwardly thereon which results in rupturing the fracturable connection of the top closure portion 22 to the adjacent parts. The swingable portion of the end wall may then be manipulated to withdraw the closure member 16 and swing it to open position as illustrated in Fig. 3. The notch 8 provides a finger opening for facilitating the removal of a packaged material such as the packages.

35 I have not illustrated and described various modifications and adaptations which might be desirable or advantageous for particular products as it is believed this

disclosure will enable those skilled in the art to embody or adapt my invention as may be desired.

Having thus described my invention, what I claim to be new and desire to secure by Letters Patent is:

1. A dispensing carton formed of an integral blank and comprising side walls and end walls provided with coacting bottom closure members, the side walls having overlapping side top closure members, one end wall having a top flap disposed on the inner side of said side top closure members, the inner of said side top closure members terminating in spaced relation to the other end wall, the outer of said side top closure members having a finger piece projecting beyond the end edge of the inner of the side top closure members, said side top closure members having aligned transverse weakened severing zones spaced from said end edge of said inner side top closure member and severing connections to their respective side walls terminating at such transverse weakened zones facilitating the removal of a portion of the top closure to provide a discharge opening for the carton by grasping said finger piece the adjacent end wall having a transverse score adjacent its upper end providing a swingable section, said swingable section having a top closure flap on its swinging edge initially disposed on the inner side of said side top closure members and being of such length as to project beyond the said transverse severing zone thereof, whereby when said severable portion of said side top closure is removed said top closure flap may be adjusted by manipulation of said swingable end wall section.

2. A dispensing carton comprising side walls and end walls, the side walls having overlapping side top closure members, the inner of said side top closure members terminating in spaced relation to end wall, the outer of said side top closure members having a finger piece projecting beyond said end edge of the inner of the side closure member, said side top closure members having aligned transverse weakened zones facilitating the removal of a portion of the top closure to provide a discharge opening for the carton by grasping said finger piece, the adjacent end wall having a transverse score adjacent its upper end providing a swingable section, said swingable section having a top closure flap on its swinging edge initially disposed on the inner side of said side top closure members and being of such length as to project beyond the said transverse severing zone thereof, whereby when said severable portion of said side top closure is removed said top closure flap may be adjusted by manipulation of said swingable end wall section.

3. A dispensing carton comprising side walls and end walls, the side walls having overlapping side top closure members, one end wall having a top flap disposed on and fixedly secured to the inner side of said side top closure members, the inner of said top closure members terminating in spaced relation to the other end wall, the outer of said side top closure members projecting beyond said end edge of the inner of said side top closure members, said side top closure members having transverse severing zones spaced from said end edge of said inner side top closure members and fracturable connections to their respective side walls terminating at such transverse weakened zones facilitating the removal of a portion of the top closure to provide a discharge opening for the carton, the adjacent end wall having a transverse score adjacent its upper end providing a swingable section, at least one edge of said swingable section initially having a fracturable connection to one side wall, said swingable end wall section having a top closure flap on its swinging edge initially disposed on the inner side of said top side closure members and being of such length as to project beyond said transverse severing zone thereof,

whereby when said severable portion of said side top closure is removed the said top closure flap may be adjusted by manipulation of said swingable end wall section.

4. A dispensing carton comprising side walls and end walls, the side walls having overlapping side top closure members, the inner of said side top closure members terminating in spaced relation to one end wall, the outer of said side top closure members projecting beyond said end edge of the inner of said side top closure members, said side top closure members having transverse severing zones spaced from said end edge of said inner side top closure members and fracturable connections to their respective side walls terminating at such transverse weakened zones facilitating the removal of a portion of the top closure to provide a discharge opening for the carton, the adjacent end wall having a transverse score adjacent its upper end providing a swingable section, said swingable end wall section having a top closure flap on its swinging edge initially disposed on the inner side of said top side closure members and being of such length as to project beyond said transverse severing zone thereof.

5. A dispensing carton comprising side walls and end walls, the side walls having overlapping side top closure members, the inner of said side top closure members terminating in spaced relation to one end wall, the outer of said side top closure members projecting beyond said end edge of the inner of said side top closure members, its end constituting a finger piece, said side top closure members having transverse fracturable zones spaced from said end edge of said inner side top closure member and fracturable connections to their respective side walls facilitating the removal of a portion of the top closure to provide a discharge opening for the carton by grasping the end of the outer of said closure members, the adjacent end wall having a swingable upper section, at least one edge of said swingable section initially having fracturable connections to one side wall, said swingable end wall section having a top closure flap on its swinging edge initially disposed on the inner side of said top side closure members and being of such length as to project beyond said transverse severing zone thereof.

6. A dispensing carton comprising side walls and end walls, the side walls having overlapping side top closure members, the inner of said side top closure members terminating in spaced relation to one end wall, the outer of said side top closure members projecting beyond said end edge of the inner of said side top closure members, its end constituting a finger piece, said side top closure members having transverse fracturable zones spaced from said end edge of said inner side top closure member and fracturable connections to their respective side walls facilitating the removal of a portion of the top closure to provide a discharge opening for the carton by grasping the end of the outer of said closure members, the adjacent end wall having a swingable upper section, said swingable end wall section having a top closure flap on its swinging edge initially disposed on the inner side of said top side closure members and being of such length as to project beyond said transverse severing zone thereof.
